ILLUMINATED SIGN WITH INTERCHANGEABLE SIGN ELEMENTS

Louis R. Tschopp, Buffalo, N. Y.

Application January 30, 1945, Serial No. 575,245

1 Claim. (Cl. 40—130)

1

This invention relates to sign structures and particularly to such structures as contemplate an assembly comprising individual shiftable elements forming letters of the alphabet or other symbols.

It has heretofore been proposed to provide sign structures having a number of letters each including means for its illumination, the individual letters having electrical connection in one fashion or another with a common current source. Devices of this nature have not thus far found general acceptance owing to various inconveniences and undesirabilities inherent in their construction.

To be practically satisfactory a sign of this nature must be durable and structurally strong; it must adapt itself readily to mounting either exteriorly or interiorly; it must provide safe and certain electrical communication; the letters of the sign and the letter receiving means must be so formed and constructed as to facilitate the ready assembly of letters with complete selectivity both as to letter arrangement and spacing; and the construction must be sufficiently simple to render the production of the several elements comprising a finished sign possible at a cost which will be within practical limits.

In my prior Patent No. 2,240,917, dated May 6, 1941, I have set forth a sign structure of the general type referred to here wherein individually shiftable illuminated sign elements are assembled into a complete sign in a novel manner. The present invention comprises improvements in the basic arrangement disclosed in the patent identified above. The present arrangement distinguishes over the patented construction chiefly in the manner in which the sign letters are introduced into and retained by the sign support element and by the manner in which electrical communication of the several elements with a power source is brought about and maintained.

An exemplary embodiment of the improvements present in the improved sign structure of the present invention is described in detail in the following specification and illustrated in the accompanying drawings in which:

Fig. 1 is a general fragmentary elevational view of a sign supporting structure having several letters associated therewith;

Fig. 2 is a fragmentary top plan view of the device with a cover element of the sign support removed for added clearness of illustration;

Fig. 3 is a cross sectional view on the line III—III of Fig. 2;

2

Fig. 4 is a fragmentary perspective view of one of the electrical contact elements;

Fig. 5 is a fragmentary cross sectional view taken on the line V—V of Fig 2; and

Fig. 6 is a fragmentary cross-sectional view showing electrical contact retaining means.

Reference will now be had to the drawings in which like characters of reference denote like parts and the numeral 10 in Fig. 1 indicates generally a supporting means for individual sign elements consisting of symbols or letters designated 11 in Fig. 1. The supporting means 10 comprises a longitudinal element of generally channel cross section. As appears clearly from Fig. 3, the supporting means 10 has an upwardly and inwardly directed flange 12 along its right edge, which is the front edge of the sign. The left edge of the sign, as viewed in Fig. 3, the rear edge of the supporting means, is built up as at 13 to house and support electrical contactor elements which form a more or less permanent part of the supporting means.

The built up portion 13 is provided with a series of aligned cylindrical openings 15 which open toward the central part of base 10 and each opening has a pair of opposite longitudinal grooves 16 formed therein for a purpose which will presently appear. Each of the openings 15 receives a cylindrical contact holder 18 which has oppositely extending ears 19 at its base. The ears 19 fit in grooves 16 and thus prevent rotation of holders 18. The portion 13 of base 10 is longitudinally slotted as at 20 to receive a bar 21 of insulating material. The bar 21 has a series of downward projections 22 which occupy substantially the entire spaces between the several cylindrical holders 18 and thus, through cooperation of ears 19, prevent removal of the holders from their openings.

The holders 18 are hollow and receive compression coil springs 23 which normally yieldably urge them to the position of the two top holders and the two bottom holders in Fig. 2. The contacts proper are best illustrated in Fig. 4 where they are designated 25 and comprise return-bent metallic body portions having their outer upper and lower edges flared outwardly as shown at 26. Each contact 25 is fixedly secured to its holder 18 in any desired or convenient manner. In the illustrated instance the contacts 25 are held in bifurcations in the holders 18 by riveting.

It will be noted that the flared outer ends of each contact are adapted to closely embrace the folded edge of the adjacent contact at one side thereof, as shown in Fig. 5. Thus, when the contacts are in alignment, or sufficiently so to be in

contact, they provide in effect a continuous electrical conductor. When one of the holders and its contact is pushed sufficiently far out of alignment, as in the case of the middle contact of Fig. 2, the continuity of the conductor is temporarily interrupted at that point. Electrical connection of the opposite end contacts of a series may be effected in any desired and conventional manner. In the illustrated instance, by way of example, such connection may be in the secondary circuit of a transformer indicated schematically at 28 in Fig. 1 and also appearing in Fig. 3.

The individual sign symbols or characters, together with their individual holders and assembling means, will now be described. Each character is formed by a continuous glass or other transparent or translucent gas filled tube whose opposite ends 30 are sealed excepting for lead-in conductors 31 and contain conventional electrodes (not shown). A holder block 32 of insulating material has semi-circular recesses in its upper surface for receiving the ends 30 of the tube and a cover block 33, likewise of insulating material has complementary recesses in its lower surface and is screwed to block 32 as at 34 to firmly clamp and support the gas filled tube. Note that the tube ends extend substantially horizontally while the symbol or character portions proper extend upwardly therefrom.

The lead-in conductors 31 terminate at exposed faces of the block 32 in longitudinally spaced electrical terminal or contact elements 40 which may seat against contacts 25 to supply electrical energy to the luminous tube. A medial extension 41 is provided upon block 32 and such extension may be formed as an integral part of block 32. This extension serves to isolate the terminals 40 of each block 32 which are disposed at opposite sides thereof.

The front face of block 32 is grooved to receive flange 12 of holder 10 and a character or symbol is placed in the holder by disposing the concave end of extension 41 against whichever contact 25 occurs at the point where the character is desired to be located longitudinally. The contact and its holder 18 is then moved rearwardly, to the left as viewed in Figs. 2 and 3, until the block 32 may be dropped down flat against the relatively flat intermediate portion of support 10, whereupon the block 32 may be released and springs 23 will move block 32 forwardly until the groove in the front thereof engages over flange 12 and the sign character or symbol is thus held in desired assembled position.

A cover 44 of insulating material is hinged to the rear edge of support 10 as at 45 to protect the exposed electrical conductors as well as to insure against inadvertent disassembly of the assembled sign elements. It will be noted that assembly of the sign character automatically breaks the continuity of current flow through the series of contacts 25 by displacing one of them

and simultaneously re-establishes current flow through engagement of the two terminals 40 with the contacts at each side of the one displaced, the new circuit including the electrodes of the neon or other luminous tube, whereby it is automatically illuminated when the main control switch of the sign is turned on.

The proportioning of the parts is such that no precaution need be taken to have the extension 41 horizontally aligned with a single contact 25. If it should happen that the extension 41, in assembling a letter, displaces two adjacent contacts 25, the terminals 40 will still make contact with two contacts 25 lying adjacent the two displaced contacts 25.

While specific details of construction have been referred to herein for the purpose of exemplification, it is to be understood that my invention is in no sense to be considered as limited thereby or in any other way save as defined in the appended claim.

I claim:

A sign element for use in combination with others in a relatively flat longitudinally channeled holder having horizontally spaced longitudinal flanges, one formed to interfit with the sign elements and the other having resilient contact elements normally urged toward the one flange; said sign element comprising a generally symbol portion and a mounting portion extending rearwardly from the base of the symbol portion, said mounting portion having a face formed to interfit with said one flange and spaced electrical terminals at its opposite face for engagement with spaced contact elements for energizing said sign element, and an insulating projection formed on said mounting portion between said terminals to disengage one of said contact elements upon assembly of said element in the holder whereby engagement of said electrical terminals with contact elements at opposite sides of the displaced contact element establishes a circuit for said sign element.

Certificate of Correction

Patent No. 2,532,651

December 5, 1950

LOUIS R. TSCHOPP

It is hereby certified that error appears in the printed specification of the above numbered patent requiring correction as follows:

Column 4, line 30, after the word "generally" insert *vertical*;
and that the said Letters Patent should be read as corrected above, so that the same may conform to the record of the case in the Patent Office.

Signed and sealed this 23rd day of January, A. D. 1951.
